Primary Examiner—Bernard Ansher*Assistant Examiner*—Lucy Lieberman*Attorney, Agent, or Firm*—John A. Doninger[57] **CLAIM**

The ornamental design for a dispenser with overcap, as shown and described.

DESCRIPTION

FIG. 1 is a side and top perspective view of the dispenser with overcap showing my new design;

FIG. 2 is a side and top perspective view thereof with the overcap exploded;

FIG. 3 is an elevational view thereof, all elevational views being the same;

FIG. 4 is a top plan view thereof;

FIG. 5 is a bottom plan view thereof;

FIG. 6 is a vertical cross-section taken along line 6—6 in FIG. 3; and,

FIG. 7 is a cross-section thereof taken along line 7—7 of FIG. 3.
